UNITED STATES PATENT OFFICE.

CHARLES H. BLISSELL, OF OIL CITY, PENNSYLVANIA, ASSIGNOR OF ONE-THIRD TO
CHARLES H. WISE, OF OIL CITY, PENNSYLVANIA.

PILOT FOR LOCOMOTIVES.

1,310,731.

Specification of Letters Patent. Patented July 22, 1919.

Application filed December 17, 1918. Serial No. 267,150.

To all whom it may concern:

Be it known that I, CHARLES H. BLISSELL, citizen of the United States, residing at Oil City, in the county of Venango and State of Pennsylvania, have invented certain new and useful Improvements in Pilots for Locomotives, of which the following is a specification.

The object, construction, and application of this invention, are herein set forth with sufficient clearness to enable those skilled in the art to which it relates, to make and use the same.

The objects of this invention are, to provide a pilot for locomotives having the following advantages:

1. A structure adapted to be quickly and easily detached from or attached to the pilot beam.
2. So constructed that the various elements comprising the structure may be easily, quickly and cheaply renewed or replaced when necessary.

3. The provision of a fore-runner or point which will prevent the pilot from picking up planks or timbers from crossings when these become raised above their proper elevations by frost or other means.

One form of construction whereby I attain these several objects is clearly illustrated in the accompanying drawings, the various figures of which are as follows:

Figure 1 is a side elevation of my improved pilot.

Figs. 2, 3 and 4, are a side elevation, front elevation, and inverted plan respectively of an element termed a bracket.

Fig. 5 is a plan view of the base, Fig. 6 is a plan view of the complete structure.

Fig. 7 is a transverse section of one side of the base at one of the sockets.

Said drawings are intended merely to illustrate one form of embodiment of my inventive idea, and are not for the purpose of limiting the same to the particular construction there shown; various modifications not only can be, but in some instances, must be employed to suit differing conditions and requirements. As usual, the precise definition of my invention must be looked for in the claims.

The construction illustrated in the drawings is substantially as follows:

The main element of this construction consists of a base, Fig. 5, of triangular shape,

which may be either wood or metal, or a combination of both these substances, that shown being a combination of wood and metal.

The wood portion of the base is indicated by the reference numeral 1, and the metal portions thereof by the reference numeral 2. By reference to Fig. 7, it will be readily understood that, as here shown, the lateral sides of said base 1 are formed into a mortise for the reception of a panel 2, preferably wood, in which panel the sockets 3 are formed.

Within said wood portions 2 of said base, a number of sockets 3 are formed, for the reception of the lower ends of the bars 4.

Pads 5 are provided upon the upper face of said base for the reception and attachment of the lower ends of the vertically extending brackets 6.

Said lower ends of said brackets are attached to said base by means of the bolts 7 and 8, which pass through holes in said elements, suitably provided for this purpose.

To the upper ends of said brackets is secured a head 9, provided with sockets 10 for the reception of the upper ends of said bars 4.

Bolts 11 and 12 serve to firmly attach said head to said brackets.

The sockets 10, in said head, preferably extend through the same so that said bars 4 may be readily inserted or removed therethrough, thus facilitating repairs and renewals.

Said brackets 6 are provided with an upwardly extending strap 6' to serve as means for the attachment of the pilot to the pilot-beam of the locomotive—said beam being indicated by the reference numeral 13 in Fig. 1.

An additional means of attaching said base and head together is provided in the bolts 14, which may be of sufficient length to also extend through said pilot beam 13, and thereby serve as additional means for attaching the pilot to said beam. An elongated socket 15 is provided in the metal portion 1 of the base for the reception of the lower end of said bolt 14 and in which said bolt has sufficient longitudinal movement to permit its disengagement from said beam without coming into contact with the floor or ground. The apex or point of the triangular base is provided with a prow or fore-runner 16, the lower face of which curves upwardly for the purpose of adapting the pilot to depress and ride over loose and high crossing-planks and

other such encroachments, rather than strike dead against the same, tear them up, and possibly, deposit them in dangerous positions upon the track, thus causing derailments or other damage or accident to the locomotive or train.

The various elements of my improved pilot are readily detachable for the purpose of renewals and repairs.

10 Suitable nut-locks, conforming to the practices of the various railways and locomotive builders, may be used upon this construction.

I claim the following:

1. A pilot for locomotives consisting of a structure comprising in combination, a base of triangular shape the lateral sides of which are provided with sockets for removably carrying the lower ends of bars, a head positioned in vertical alinement with the rearward member of said triangular base and provided with sockets for removably carrying the upper ends of said bars, bars mounted in said sockets, brackets uniting said base and said head, and means for attaching said structure to the pilot beam of a locomotive.

2. A pilot for locomotives consisting of a structure comprising in combination, a triangular frame or base having the apex thereof extended to form a fore-runner and provided with sockets for the reception of the lower ends of bars, a head provided with sockets for the reception of the upper ends of said bars, bars mounted in said sockets, brackets rigidly connecting said base and said head together, and means for attaching said structure to the pilot beam of a locomotive.

3. A pilot for locomotives comprising, in combination, a triangular frame or base the apex of which is formed into an upwardly-curved, forwardly-projecting fore-runner, the lateral sides of said base being provided with sockets for the reception of the lower

ends of bars, a head provided with sockets for the reception of the upper ends of said bars, bars insertible into and removable from said sockets by a longitudinal movement thereof through the sockets of said head, means securing said base and said head together, and means for attaching the structure so-formed to the pilot-beam of a locomotive.

4. A pilot for locomotives comprising in combination, a triangular base, the lateral sides of which are provided with sockets for the reception of the lower ends of bars, an upwardly-projecting bolt-socket carried by said base, a head provided with sockets for the reception of the upper ends of said bars, bars insertible into said sockets and removable therefrom through said sockets in said head, brackets securing said base and said head together, and a bolt carried by and adapted to have longitudinal movement in said bolt-socket, adapted to pass through the pilot beam and to serve as means for securing said pilot to said pilot-beam.

5. A pilot for locomotives comprising in combination, a triangular base the lateral sides of which are mortised for the reception of a panel respectively, a panel carried by each of said mortises and provided with sockets for the reception of the lower ends of bars, a head provided with sockets for the removable reception of the upper ends of said bars, bars removably carried by said sockets, means securing said base and said head together, and means for attaching the structure so-formed to the pilot-beam of a locomotive.

In testimony whereof I affix my signature in presence of two witnesses.

CHARLES H. BLISSELL.
